UNITED STATES PATENT OFFICE.

GEORGE G. SCHUELE, OF CLEVELAND, OHIO.

COVER-RELEASING DEVICE.

1,160,204.

Specification of Letters Patent. Patented Nov. 16, 1915.

Application filed November 3, 1913. Serial No. 798,903.

To all whom it may concern:

Be it known that I, GEORGE G. SCHUELE, citizen of the United States, residing at Cleveland, in the county of Cuyahoga and 5 State of Ohio, have invented certain new and useful Improvements in Cover-Releasing Devices, of which the following is a specification.

This invention relates to improvements in 10 cover releasing devices for containers, especially small cans or boxes having tightly-fitting covers, and the improvement comprises a simple and inexpensive slide-member to effect easy release of the cover, either 15 by finger pressure or by engagement of the slide-member with a fixed object.

In the accompanying drawings, Figure 1 is a perspective view of a round container 20 embodying my improvement and showing one manner in which the parts may be held in the hands and engaged by the fingers for convenient removal of the cover. Fig. 2 is a side view of the container showing the cover in place and the slide member in inoperative position. Fig. 3 is a similar view to 25 Fig. 2, but showing the cover partly released by the slide member. Fig. 4 is an enlarged sectional view of the container and slide member on line 4-4; Fig. 2. Fig. 5 is a 30 sectional view of a modified form of container.

In Figs. 1 to 4, the container comprises a round box 2 of thin metal and a cover 3 of 35 the same material fitting tightly thereon. The circular wall 4 of the body of the box is inturned at its upper edge 5 to facilitate the placing of the cover thereon, and wall 4 is also shown as having a bead 5' partly about the same to limit the seating depth of 40 the cover. The flange 6 of cover 3 is also provided with an annular bead 7 a short distance above its edge 8. In Fig. 5, the flange of the cover 9 has an inwardly-projecting bead 10 to rest on the upper edge 5 of wall 4 of the body of the box, and the bottom 45 edge 11 of the cover is flared or turned outwardly. My improvement is applicable to either form of container as it comprises a slide member 14 secured to the outside face 50 of wall 4 by means of one or more studs or rivets 15, said slide member comprising a relatively thin and long plate curved lengthwise to conform in shape to the circular wall 4 and bearing loosely against it for free 55 movement circumferentially of the box and

parallel with the bottom edge of the cover. A straight slot 16 extends lengthwise of member 14 at any suitable pitch or inclination relatively to the straight bottom edge of the cover, and a rounded part 18 at each 60 end of the top edge of said member is adapted to have slidable engagement with the bottom surface of the bead 7 on the cover 3, Figs. 1 to 4, or with the flaring edge 11 of the cover 9, Fig. 5. If a single stud 65 or rivet 15 is used its shank portion 19 which passes through slot 16 is preferably squared or flattened to prevent a rotative movement of slide member 14 at all times, and when said member is pressed to the left by its 70 outwardly-bent extremity 20 the said member is forced to a higher level and the cover 3 (or 9) is lifted in a corresponding degree. The rounded parts 18 provide two widely-separated points of bearing throughout the 75 slidable movement of member 14, which is of advantage in equalizing and distributing the force of the movement over an extended area in a relatively thin wall.

Removal of the cover may be effected by 80 holding the box in the hands as illustrated in Fig. 1, or the cover may be removed by the use of one hand only and without taking a finger grip on slide member 14. To practise the latter method, the box is held 85 between the thumb and fingers of one hand and the extremity 20 of the slide member is pressed downward against any fixed object, such as the projecting edge of a table or chair. Obviously, this is of advantage to a 90 one-armed person, or to any other person having use of one hand only. In placing the cover back on the box it is of course essential to lower or retire the slide member 14, and this may be accomplished by one 95 hand also, either by turning the box rotarily, or by merely holding the box edge-wise for an instant to permit the said member to drop by gravity into the desired re-tired position.

What I claim is:

A circular container having a removable cover with an outwardly projecting bead about its bottom portion, in combination with the body of the container and a lift 105 mechanism on one side of said body for said cover comprising a plate curved lengthwise to conform to the curvature of the container and having upwardly extending portions at its ends and edge adapted to bear against 110

said annular bead and provided with an outwardly extending finger grip at one end and a diagonally disposed slot, and a stud rivet through said slot engaging said plate slidably on said body and having a square shank in said slot to prevent rotation of said plate.

In testimony whereof I affix my signature in presence of two witnesses.

GEORGE G. SCHUELE.
